D. BRAY.

CARDING ENGINE AND LIKE MACHINE.

APPLICATION FILED MAY 13, 1919.

1,369,776.

Patented Mar. 1, 1921.

UNITED STATES PATENT OFFICE.

DAVID BRAY, OF SHIPLEY, ENGLAND.

CARDING-ENGINE AND LIKE MACHINE.

1,369,776.

Specification of Letters Patent.

Patented Mar. 1, 1921.

Application filed May 13, 1919. Serial No. 296,760.

To all whom it may concern:

Be it known that I, DAVID BRAY, a subject of the King of Great Britain, and resident of 17, Redburn Road, Shipley, in the county 5 of York, England, have invented a certain new and useful Improvement in Carding-Engines and like Machines, of which the following description, having reference to the accompanying sheets of drawings, is a 10 specification.

My invention relates to feeding mechanism for carding and like machines used in the treatment of fibrous substances and consists of the application of devices whereby 15 any matted fibers (such as entangled fibers of wool) are combed or torn asunder prior to being fed to the carding or like cylinder. The feeding rollers at present made use of (especially in connection with the feeding of 20 wool or the like to the main cylinder) consist of two feeding rollers having comparatively large teeth for pulling asunder and feeding the wool or the like to a third roller which transfers said fiber to the main cylinder. 25 The teeth of the two rollers first before mentioned are arranged to intersect each other so as to carry out the functions well known, but in the employment of these devices it is often found that matted or entangled fibers 30 are fed to the main cylinder and are not properly treated. The object of my invention is to produce devices and operate same in such a manner as to obviate or practically avoid the feeding of matted fibers to the 35 main cylinder.

In order that my said invention may be readily understood, I have hereunto appended sheets of drawings illustrative thereof, to which by letters and figures reference 40 is made in the following description.

Figure 1 is a sectional side elevation showing the main cylinder of a carding engine or the main drum of a willoying machine or of a machine of a similar character, with the 45 feed rollers and my improved parts mounted relatively thereto as hereinafter described.

Fig. 2 is an elevation of the parts shown by Fig. 1, with devices for transmitting motion to the parts arranged in accordance 50 with my invention.

Fig. 3 is a plan of the parts shown by Fig. 2.

The framework for supporting the several parts which are illustrated by the drawings, 55 is omitted for the reason that such frame-

work may vary according to the particular type or class of machine or to the particular design of any respective producer of said machine, as said framework forms no part of my invention.

A indicates the first cylinder or first licker in, of a carding engine or the main drum of a like machine employed for similar purposes.

To attain the object of my invention I 65 make use of the usual pair of feed rollers *a* and *b* which have comparatively coarse or large teeth 2, 3, so that the fibrous substances may be fed thereto as by the traveling apron *c* in manner well known, the feeding actions 70 of said brattice *c* and the two rollers *a* and *b* are carried out by the motions of same being in the direction indicated by the arrows 4, 5 and 6 respectively. The driving mechanism for the said rollers *a* *b* and the 75 brattice *c* are of well known formation and arrangement as at present in use.

Instead of making use of a third feed roller as heretofore, I now make use of a semi-cylindrical roller *d* (or this may be a 80 complete roller as shown by Fig. 3, when such is desired to be changed so that on one part of the surface being worn or damaged the other part or surface thereof may be brought into use as is hereinafter explained) and this semi-cylindrical roller is mounted in proximity to the upper roller *b* of the usual pair of feed rollers *a* and *b* as is the third roller heretofore employed. 85

The teeth of the semi-cylindrical roller *d* 90 are of similar character to those of the rollers *a* and *b* and are arranged to point in the direction illustrated by Figs. 1 and 2 while the teeth of the rollers *a* and *b* also point in the respective directions indicated 95 by Fig. 1.

I cause the semi-cylindrical roller *d* to oscillate about its shaft 7 by having a pinion *e* fixed upon said shaft 7. This pinion is arranged to gear with a quadrant *f* mounted loosely upon the shaft 9 so that its horizontal arm *f* may be connected by a rod *g* to a crank *h* arranged to rotate upon its shaft *k* as driven by the chain wheel *m* shown by Figs. 2 and 3. Or the oscillatory 100 motions of the semi-cylindrical roller *d* may be effected or secured by any other well known mechanical devices deriving their motion from any motor part of the machine to which my invention is applied, 105 110

and which arrangement will be well understood by those having a knowledge of this character of mechanism.

The arrangement of sprocket wheel *m* 5 and its chain *n* as shown by Figs. 2 and 3 is only to show one device that might advantageously be employed, and which might be brought to be situated in appropriate proximity to the semi-cylindrical roller to 10 which I desire to transmit oscillatory motion.

The semi-cylindrical roller *d* has teeth 8 made to mesh or intersect with the teeth of the roller *b* and the oscillations of the 15 semi-cylindrical roller *d* are arranged to be derived from such motor part of the machine as will enable its oscillatory movements to be at a comparatively high speed that is to say, whereas the rotary motions 20 of the two feed rollers *a* and *b* may be about or approximately four revolutions per minute the oscillations of the semi-cylindrical roller are to be approximately one hundred per minute, thus no matted 25 fibers carried through the feed rollers *a* and *b* can pass in their said matted condition beyond the oscillating surface or teeth 8 of the roller *d* for the reason that the said teeth 8 of the semi-cylindrical roller *d* will 30 tear or detach such fibers from the upper feed roller *b* and in such direction as to carry the detached fibers toward so as to be fed to the first cylinder A of the machine, which cylinder A takes said fibers and carries 35 them forward in well known manner. The advancing of the teeth 8 of the semi-cylindrical roller as described effects the feeding of the fibers to the main cylinder *a* while the receding motions of said teeth 8 have 40 been found to have the effect of clearing the teeth 3 of the feed roller *b*, hence in addition to the prevention of matted fibers being fed to the main cylinder A the apparatus described also prevents any accumulation 45 of same on the feed rollers in connection with which it is used.

As is hereinbefore stated, instead of the semi-cylindrical roller *d* being made use of, I may use a roller arranged so that when 50 the teeth of one section thereof are worn or become damaged then another section or portion of the periphery of said roller may

be brought into use so that the teeth extending therefrom will carry out the functions desired.

55

The space or path through which the oscillations of the periphery of the roller *d* is or may be carried out at each oscillation is preferably about one third the circumference of said roller, although it is obvious that this may be varied as may be found advantageous, and such variations may be effected by the adjustment of the sweep of the crank *h* or the position in which the rod *g* is connected to the arm *f*¹ of the quadrant *f*.

60

Such being the nature and object of my said invention, what I claim is:—

1. In a carding engine or like machine, a carding cylinder having its teeth bent in 70 the direction in which it rotates, a pair of feed rollers with their teeth bent in the opposite direction to that in which they rotate, adjustable bearings for said rollers to enable the teeth of these latter to be situated to operate close to the teeth of the carding cylinder, a semi-cylindrical roller having teeth bent in an opposite direction to the teeth of the feed roller to which it is adjacent, said teeth of the semi-cylindrical roller engaging with the teeth of said feed roller, and means whereby oscillatory motion is transmitted to the semi-cylindrical roller.

75

2. In a carding engine or like machine, a 85 carding cylinder having its teeth bent in the direction in which it rotates, a pair of feed rollers, one of said feed rollers having its teeth adjacent to the teeth of the carding cylinder and bent to point in the same direction as said teeth of the carding cylinder, a second feed roller having its teeth engaging with the teeth of the first feed roller and pointing in the same direction at the point of engagement, a semi-cylindrical 90 roller having its teeth engaging with those of the second feed roller and bent in the same direction as the teeth of the carding cylinder but not in engagement with said teeth of the carding cylinder, and devices 100 for transmitting oscillatory motion to said semi-cylindrical roller.
